UNITED STATES PATENT OFFICE.

OLIN H. BASQUIN, OF CHICAGO, ILLINOIS, ASSIGNOR TO THE LUXFER PRISM PATENTS COMPANY, OF SAME PLACE.

DESIGN FOR A PRISM-LIGHT.

SPECIFICATION forming part of Design No. 27,823, dated July 13, 1897.

Application filed June 15, 1897. Serial No. 640,919. Term of patent 14 years.

To all whom it may concern:

Be it known that I, OLIN H. BASQUIN, a citizen of the United States, residing at Chicago, in the county of Cook and State of Illinois, 5 have invented and produced a certain new and useful Design for Prism-Lights, of which the following is a description.

My design consists of a prism-light having a certain outline with an inscribed smaller 10 circular prism-surface. It is illustrated in the accompanying drawings, wherein—

Figure 1 is a plan view of a hexagonal prism-light. Fig. 2 is a section therethrough. Like parts are indicated by the same letter 15 in both figures.

A is the body of the prism-light, B B the

prisms, and C one of the corner-pieces, non-prismatic.

I have shown the prism-plate as hexagonal and a certain arrangement of angles and proportions in the prisms and the plate; but the essential features of my design are found in a prism-light having an inscribed circular prism-surface smaller than and of different shape from the outline of the prism-light. 20 25

I claim—

The design for a prism-light substantially as shown and described.

OLIN H. BASQUIN.
